UNITED STATES PATENT OFFICE.

JAMES EDWIN DEMPSEY, OF CHICAGO, ILLINOIS.

TELEGRAPHIC CODE.

SPECIFICATION forming part of Letters Patent No. 703,391, dated July 1, 1902.

Application filed April 19, 1899. Serial No. 713,673. (No model.)

To all whom it may concern:

Be it known that I, JAMES EDWIN DEMPSEY, a citizen of the United States, residing at Chicago, in the county of Cook and State of Illinois, have invented certain new and useful Improvements in Telegraphic Codes; and I do hereby declare the following to be a full, clear, and exact description of the invention, such as will enable others skilled in the art to which it appertains to make and use the same.

This invention relates to improvements in what is generally known as a "cipher-code" used in transmitting messages by telegraph, and has for its object, primarily, to provide a means or system by which telegraphic communications may be transmitted at a great reduction in cost and at the same time provide a permanent code-book and a changeable code-book key to be used in connection therewith. The code-book key is entirely separate matter from the code-book, so that a new key may be devised as often as necessary and the same code-book used indefinitely, thus practically getting a new code with each new key and saving the time, labor, and expense of formulating a new code-book when a change in the system is required.

Another important object is the great saving in expense of transacting a railroad or commercial business by telegraph, as with this system the amount of matter in ordinary cipher-codes that is expressed by one word is covered in this cipher by a single letter, syllable, or part of a word. An absolutely secret and economical system of ciphering is thus provided, the operation of which is hereinafter explained.

The code-book contains words, phrases, sentences, &c., which are arranged in column order, with a number directly opposite each. These numbers appear in the code-book key, which is prepared separately from the code-book and arranged in columns in consecutive order, the range of the numbers in the code-book key being sufficient to represent the highest number which appears in the code-book, and directly opposite each number thus arranged is placed a syllable which represents that number in code-words which are formed therefrom. The code-book key also contains certain additional numerals, also fractions, words, sentences, signs, and characters, which

are arranged in column order and which have directly opposite each a letter, letters, syllable, or word which represent the same when forming code-words to be sent over the wire.

This cipher-code can be used generally, but is more especially devised for the use of railroads, corporations, and commercial houses, who necessarily have to transact the bulk of their business by wire, so that secrecy and the question of a saving economy in the transmission of messages are very important features.

This improved method or system of ciphering differs materially from the "ordinary telegraph code," in that—

First. The system is complete in two parts, consisting of a code-book and a code-book key, which are entirely separate and apart from each other.

Second. The matter in the code-book is represented by numerals, the pages being numbered in consecutive order, as is also each line of literary matter printed on each page, every line of matter on each page having a numeral directly opposite it.

Third. The code-book key is printed on a card or folder entirely separate from the code-book and is divided into three sections, as follows:

Section 1 is the key proper to the code-book and contains the numerals from "1" upward to any desired number, the range of the numbers in the key being sufficient to represent the largest number which appears in the code-book. These numerals are arranged in column order and have directly opposite each a syllable to represent that number in code-words formed therefrom.

Section 2 of the code-book key is an auxiliary code and contains such fractions and numerals as do not appear in or cannot be formed by joining any of the combinations or syllables in section 1. These fractions and numerals are arranged in column order, and there is placed directly opposite each number and fraction a syllable which will represent that particular number or fraction in code-words in which it appears.

Section 3 of the code-book key is an auxiliary code and contains such signs, words, and phrases as are commonly used in commercial business to assist sections 1 and 2 in cipher-

ing and deciphering matter. These signs, words, and phrases are arranged in column order, and there is placed directly opposite each a letter, letters, syllable, or word which stands for and represents that particular line of matter in the code-words in which they appear.

By the joint use of the three sections of the code-book key any fraction, per cent., time of day, quantity, &c., can be ciphered into a single syllable or word. Any letter, syllable, or word and joined to code-words formed from syllables in section 1 of the key completely changes the meaning of that group so formed, 15 the preceding word or syllable being governed by the meaning of the letter, word, or syllable from section 3 so affixed, and by the use of the three sections jointly any numerical combination desired can be expressed 20 without any reference to the code-book.

Fourth: The exchanging of numerals which appear in the code-book for syllables which are found in section 1 of the code-book key and which represent said numbers, such syllables being joined to other syllables until a word of any desired length is formed.

In the accompanying drawings, Figure 1 is an illustration of a part of the first page of my code-book, showing a column of numerals, 30 beginning with "1" at top of page and running downward in regular numerical order to any desired number. Opposite each of the numerals is a series of words, phrases, or sentences in column order alphabetically arranged. Fig. 2 illustrates a part of section 1 of the code-book key used conjointly with the code-book in framing or coining the code-words and in deciphering or in arriving at a solution of the matter that is intended to be 35 sent by telegraph. Figs. 3 and 4 illustrate parts of section 2 of the code-book key used as an auxiliary code in forming certain combinations of numerals not otherwise provided for. Fig. 5 is an illustration of section 3 of 40 the code-book key used as an auxiliary code, containing certain signs, words, sentences, &c., to be used as hereinafter explained. Fig. 6 is an illustrated example showing how 45 the numeral "18" would be ciphered by reference to the key, Figs. 2 and 5; and Fig. 7 is an example showing how the matter in the code-book, Fig. 1, may be ciphered by reference to the code-book key, Fig. 2.

The pages of the code-book will usually be 50 numbered in regular order from "1" upward, and ordinarily the words, symbols, and characters used in the code-book key will not appear in the code-book.

The numerals and the words, phrases, and 55 sentences in the code-book are arranged in parallel columns, and each line containing words, phrases, and sentences will be controlled by the numeral directly opposite.

The matter on each and every page in the 60 code-book will be numbered in precisely the same manner as illustrated in Fig. 1—viz., beginning with "1" at the top of the page

and continuing in consecutive order to the bottom of the page.

By reference to Fig. 1 it will be noted that 70 the lines run "1" to "15" and may be continued according to the length of the page and arrangement of the matter printed thereon.

To transform a message or communication into cipher under my system, the rule is to 75 proceed by referring to the numerals, each numeral in the code-book being represented in the code-book key by a syllable, and by the grouping of such syllables the code-words are formed. The first syllable of the code-word indicates the number of the page of the code-book on which the words, phrases, or sentences will be found, and the second syllable of the code-word indicates the number 80 of the line on that page, as illustrated by the 85 example in Fig. 7.

By reference to Fig. 1 it will be noted that the words "Any quantity" appear on page 1, line 8, of the code-book. In ciphering these words the numerals "1" and "8" are transformed into a code-word. This is done by referring to Fig. 2, which represents a part of section 1 of the code-book key used in connection with the code-book, in which we find that the numeral "1" is represented by 90 the syllable "Ba" and the numeral "8" by the syllable "Ci," which when placed together in the order given form the code-word "Baci," meaning in the language of the code-book "Any quantity." The same rule governs throughout the entire code-book.

The form of key shown in Fig. 2 and used as a practical illustration is made up of mono-syllables representing numerals from "1" up to any desired number. The portion of the 105 code-book key shown in Fig. 3 is used for the purpose of assisting in ciphering communications containing a combination of numerals not provided for in section 1 of the code-book key, Fig. 2, and Fig. 4 is a continuation 110 of Fig. 3.

In Fig. 5 is shown a collection of words, phrases, signs, and sentences which are commonly used in business transactions and which have placed directly opposite thereto 115 symbols that represent them when used in connection with sections 1 and 2 of the code-book key, as illustrated by the following explanation. In ciphering "One A. M." it is necessary to refer to Fig. 2, where it will be 120 found that "One" is represented by the syllable "Ba," and to Fig. 5, where it will be found that "A. M." is represented by the symbol "Dom," which when joined together form the code-word "Badom," meaning 125 "One A. M." By following this same rule any time of day can be expressed in a single word. "One car-load" would be expressed by adding the symbol "Y," Fig. 5, to the syllable "Ba" in Fig. 2, which forms the word 130 "Bay," meaning in the language of the code-book "One car-load." By adding the symbol "S" to any combination in a similar manner the phrase "Less than car-loads" is ob-

tained. To further illustrate, suppose it is desired to cipher the clause "Carboys, less than car-loads." By reference to Fig. 1 it will be found that the word "Carboys" appears on page 1, line 15, of the code-book, and by following the rule above referred to and by reference to Fig. 2, the first section of the code-book key, we get the syllables "Ba" and "Du," which when placed together form the code-word "Badu," meaning "Carboys." To obtain the phrase "Less than car-loads," the symbol "S" on line 4 of Fig. 5, which is section 3 of the code-book key, is affixed or added to the code-word "Badu," forming the code-word "Badus," expressing in the language of the code-book the phrase "Carboys, less than car-loads." The symbol "Ys," line 5 of Fig. 5, may be used in a similar manner in ciphering into and out of communication, differing only in the meaning—viz., "Car-loads and less."

The symbol "Ski," line 6 of Fig. 5, is used as a suffix in connection with code-words formed from section 1 of the code-book key and intended to express certain numerals, such as numbers of cars, packages, shipments, &c. For example, the number "319" would be ciphered by referring to section 1 of the code-book key, Fig. 2, in connection with Fig. 5, taking the syllable "Bi," meaning "3," and the syllable "Fo," meaning "19," and by placing the two syllables together we form the code-word "Bifo," meaning "319," and by adding the symbol "Ski" to the code-word "Bifo" the code-word "Bifoski" is formed, indicating that the previous numbers which the syllables represent are to be understood literally and should not be looked for in the code-book. It will therefore be understood that section 1 of the code-book key to my cipher-code has two distinct functions: first, in deciphering words, phrases, sentences, &c., found in the code-book, and, second, by forming any numerical combination desired in connection with sections 2 and 3 of the code-book key, which function is entirely separate from and independent of the code-book proper and is to that extent an auxiliary code. All the other symbols and characters in section 3 of the code-book key, Fig. 5, are employed in a similar manner and are worked on the same principle, as per the following examples:

Symbol: "Son"—cents per 100 lbs.

55 18 cents per 100 lbs—{ Fi—18
Son—cents per 100 lbs. }—Fison.

Symbol: "De"—dollar-sign (\$).

\$19.00—{ De—\$
Fo—19 }—Defo.

60 Symbol: "Gun"—"instant."

20th instant—{ Fu—20
Gun—instant }—Fugun.

The symbols "Bam" and "Man," meaning "proximo" and "ultimo," respectively, are used in similar manner as the preceding symbol "Gun."

The symbol "Za" is used to indicate that

the syllable immediately before it (representing a number in the code-book key) is to be considered the numerator of a fraction and the syllable immediately following it (which also represents a number in the code-book key) is the denominator, performing the same function as the line in such a case. For instance, the fraction " $\frac{1}{2}$," by reference to Figs. 2 and 5, would be expressed in the following manner:

$\frac{1}{2}$ —{ Ba—1
Za—/
Be—2 }—Bazabe.

The symbol "Vy" represents a per-cent. sign ("%) and will be used in the code in the following manner:

19%—{ Fo—19
Vy—% }—Fovy.

Symbol: "Ro"—space, blank, or dash. This symbol will be used in separating characters when necessary. For instance: "18 and 19" to be read literally (by reference to Figs. 2 and 5) would be written as follows:

18 and 19—{ Fi—18
Ro—space
Fo—19 }—Firofo.

It will be readily seen that the representation of any quantity by its appropriate characters and signs is possible under the system and method herein set forth, the changes that can be made in the key being almost endless.

Under this system I have compiled a code-book of some one hundred and fifty pages, involving long and arduous labor, attended by great expense in printing the same, and by simply preparing a new key the entire code may be radically changed without making the least change in the code-book.

Having thus described my invention, what I claim, and desire to secure by Letters Patent, is—

1. In a cipher-code, a code-book having words, phrases and sentences arranged in columns therein, the pages of the book being numbered and the words, phrases and sentences on each page being also numbered, a code-book key comprising within its range all the numbers employed to designate pages of the book or words, phrases, and sentences therein, the numbers of the key having associated therewith arbitrarily-selected syllables, whereby such syllables may be combined to represent words of the code-book, as set forth.

2. In a cipher-code, a code-book having words, phrases and sentences arranged in columns therein, the pages of the book and the words, phrases and sentences on each page being numbered consecutively, a code-book key comprising within its range all the numbers employed to designate pages of the book or words, phrases and sentences therein, the numbers of the key having associated therewith arbitrarily-selected syllables, whereby such syllables may be combined to represent words of the code-book, as set forth.

3. In a cipher-code, a code-book having

- words, phrases and sentences arranged in columns therein, the pages of the book and the words, phrases and sentences on each page being numbered, a changeable code-book key comprising within its range all the numbers employed to designate pages of the book or words, phrases and sentences therein, the numbers of the key having associated therewith arbitrarily-selected syllables whereby such syllables may be combined to represent words of the code-book, as set forth.
4. In a cipher-code, a code-book having words, phrases and sentences arranged in columns therein, the pages of the book being numbered and the words, phrases and sentences on each page being also numbered, an independent code-book key comprising within its range all the numbers employed to designate pages of the book or words, phrases and sentences therein, the numbers of the key having associated therewith arbitrarily-selected syllables, whereby such syllables may be combined to represent words of the code-book, as set forth.
5. A code-book key comprising within its range all the numbers employed to designate pages, words, phrases and sentences in a code-book, the numbers of the key having associated therewith arbitrarily-selected syllables, whereby such syllables may be combined to represent words of the code-book, as set forth.

6. A cipher-code, comprising a code-book containing a part of the message or information it is intended to transmit, and an independent, changeable code-book key, prepared separately from the code-book, and having associated therewith certain characters and symbols whereby it is possible to change a code-word having one expression or meaning into another expression by affixing thereto a character or symbol provided for in the code-book key, as set forth. 35

7. In a cipher-code, a permanent code-book, having words, phrases and sentences arranged in columns therein, the pages of the book being numbered and the words, phrases and sentences being also numbered, but containing no code-words or parts thereof, a changeable auxiliary code and code-book key, prepared separate from the code-book and containing syllables, characters and symbols arranged in column order and used jointly in ciphering and deciphering, whereby it is possible to provide a new code as often as necessary by formulating a new auxiliary code and code-book key, the permanent code-book being retained indefinitely, as set forth. 45 50

In testimony whereof I affix my signature in presence of two witnesses.

JAMES EDWIN DEMPSEY.
